(57) **CLAIM**

The ornamental design for a suspended knife holder, as shown and described.

DESCRIPTION

FIG. 1 is a left front perspective view of a suspended knife holder illustrating my new design;

FIG. 2 is a top plan view further illustrating my design;

FIG. 3 is a front elevational view thereof;

FIG. 4 is a side elevational view thereof;

FIG. 5 is a bottom plan view thereof;

FIG. 6 is a rear elevational view thereof;

FIG. 7 is a left front perspective view of a second embodiment of FIG. 1, the only difference being the detachment of a single identical unit and detachment of a single identical bolt, it being understood that the broken lines are for illustrative purposes and form no part of the design;

FIG. 8 is a longitudinal sectional view through line 8—8 of FIG. 2 illustrating the internal construction of a first embodiment of FIG. 1, wherein the broken lines are for illustrative purposes and form no part of the design; and,

FIG. 9 is a left front perspective view of a third embodiment of FIG. 1, the only difference being the addition of three identical units.
